US00D631957S

(12) **United States Design Patent**
Perez et al.

(10) **Patent No.:** US D631,957 S
(45) **Date of Patent:** ** Feb. 1, 2011

(54) **SWAB**

(75) Inventors: **Juan J. Perez**, 2331 Frick Rd., Suite 206, Houston, TX (US) 77038; **Stormy L. Perez**, Houston, TX (US); **Billie Lane Walker**, Spring, TX (US)

(73) Assignee: **Juan J. Perez**, Houston, TX (US)

(**) Term: **14 Years**

(21) Appl. No.: **29/338,014**

(22) Filed: **Jun. 3, 2009**

(51) **LOC (9) Cl.** **24-02**

(52) **U.S. Cl.** **D24/119**

(58) **Field of Classification Search** D24/108, D24/119, 147; D28/7; 604/1, 2, 3; 606/162
See application file for complete search history.
